UNITED STATES PATENT OFFICE.

HENRY GOLDENFARB, OF LONDON, ENGLAND.

CIGARETTE.

SPECIFICATION forming part of Letters Patent No. 606,537, dated June 28, 1898.

Application filed October 4, 1897. Serial No. 654,055. (No model.) Patented in England September 15, 1893, No. 17,387, and November 2, 1893, No. 20,807, and in Germany November 6, 1894, No. 83,592.

To all whom it may concern:

Be it known that I, HENRY GOLDENFARB, a subject of the Queen of England, residing at 21 Great Eastern street, London, England, have invented certain new and useful Improvements Relating to Cigarettes, (for which I have received Letters Patent in Great Britain, No. 17,387, dated September 15, 1893, and No. 20,807, dated November 2, 1893, and in Germany, No. 83,592, dated November 6, 1894,) and I do hereby declare that the following is a full, clear, and exact description of the invention, which will enable others skilled in the art to which it appertains to make and use the same.

The objects of this invention are to make the tips or ends of cigarettes so that they shall not stick to the lips and shall be cool when smoking; further, to prevent the nicotine from the tobacco in the cigarettes from entering the mouth.

According to this invention I surround the top end of the cigarette with straw, (preferably Japanese straw or the like.) One way of carrying this into effect is to split the lengths of straw open and cement such lengths onto linen or paper and then cut the same into strips (crosswise of the grain) of the desired width and then cut same into lengths sufficient to go round the top end of the cigarette, which lengths may be cemented on. I further roll or otherwise insert a plug of wool, cotton, or any other suitable absorbent material in the cigarette toward the end to be placed in the mouth, but separated from that end by a thickness of tobacco.

In order that my said invention may be fully understood, I will now proceed to describe the same, with reference to the drawings accompanying this specification, in which—

Figure 1 is a view of a cigarette complete; Fig. 2, a detail hereinafter referred to; Fig. 3,

an end view at top of cigarette, and Fig. 4 a longitudinal section of a cigarette made according to my invention.

The same letters of reference are employed to denote the same parts in all the views.

a shows the cigarette and *b* the mouthpiece, consisting of a piece of straw (preferably Japanese straw,) cemented onto a piece of linen *c*. This is then fixed round the top of the cigarette and forms the mouthpiece.

Fig. 2 is a sectional view of mouthpiece, in this figure the linen back *c* being shown up-
permost.

d shows the absorbent material. It will be seen that this material is embedded in the tobacco, so as to leave a thickness of the latter between the said material and the upper end of the cigarette, thus keeping the said material in position and preventing the heat from the same from reaching the mouth.

I am aware that devices having this latter object have been used in which wool or other suitable absorbent has been placed in the end of the cigarette next to the mouth; but this has always proved objectionable, as the wool becomes heated or comes away in pieces, requiring an additional tube to keep it in position.

Having fully described my invention, what I claim, and desire to secure by Letters Patent, is—

A cigar or cigarette having a plug of absorbent material located near the end to be placed in the mouth and also provided with a mouthpiece composed of straw split and cemented to a retaining-band, said mouthpiece being cemented to the outside of the wrapper of the cigar or cigarette, substantially as described.

HENRY GOLDENFARB.
